LAZY SUSAN

Bernard Heller, Westfield, N.J., assignor to Viking Stainless Co., Inc., Newark, N.J., a corporation of New Jersey

Filed Sept. 12, 1960, Ser. No. 62,099

Term of patent 14 years

(Cl. D44—10)

FIG. 1 is a perspective view of a Lazy Susan, showing my new design.

FIG. 2 is an elevation thereof.

FIG. 3 is a top plan view thereof.

FIG. 4 is a fragmentary cross-sectional view as seen in the direction of the arrows along line 4—4 of FIG. 3.

The characteristic feature of my design resides in the combination of a platter portion of "bowed square" periphery and arcuate bottom with interfitting dishes having bottoms conforming with the bottom of the platter portion, all as shown.

I claim:

The ornamental design for a Lazy Susan, substantially as shown and described.
